[57] CLAIM

The ornamental design for a manual operator for circuit breaker, as shown and described.

DESCRIPTION

FIG. 1 is a perspective view of a circuit breaker showing my new design, the portion shown in broken lines being for illustrative purposes only;

FIG. 2 is a top plan view of the circuit breaker;

FIG. 3 is a right side elevational view thereof;
FIG. 4 is a front elevational view thereof, the rear elevational view being a mirror image; and
FIG. 5 is a left side elevational view thereof.
